[57] CLAIM

The ornamental design for a prismatic area light, as shown and described.

DESCRIPTION

FIG. 1 is a front elevation view of a first embodiment of the

prismatic area light. The rear elevation view is identical thereto;

FIG. 2 is an elevation view of the right side of the prismatic area light of FIG. 1. The elevation view of the left side is identical thereto;

FIG. 3 is a bottom plan view of the prismatic area light of FIG. 1;

FIG. 4 is a top plan view of the prismatic area light of FIG. 1;

FIG. 5 is a front elevation view of a side-mount embodiment of the prismatic area light;

FIG. 6 is a rear elevation view of the prismatic area light of FIG. 5;

FIG. 7 is an elevation view of the right side of the prismatic area light of FIG. 5;

FIG. 8 is an elevation view of the left side of the prismatic area light of FIG. 5;

FIG. 9 is a bottom plan view of the prismatic area light of FIG. 5; and,

FIG. 10 is a top plan view of the prismatic area light of FIG. 5.
